UNITED STATES PATENT OFFICE.

GEORGE U. WEIFFENBACH, OF ADRIAN, MICHIGAN, ASSIGNOR TO THE GIBFORD-WEIFFENBACH COMPANY, OF ADRIAN, MICHIGAN, A CORPORATION OF MICHIGAN.

DESIGN FOR A SWIVEL-CLAMP FOR RAZOR-STROPS OR THE LIKE.

48,430.

Specification for Design.

Patented Jan. 4, 1916.

Application filed July 6, 1915. Serial No. 38,324. Term of patent 3½ years.

To all whom it may concern:

Be it known that I, GEORGE U. WEIFFENBACH, a citizen of the United States, residing at Adrian, in the county of Lenawee and State of Michigan, have invented a new, original, and ornamental Design for a Swivel-Clamp for Razor-Strops or the like, of which the following is a specification, reference being had to the accompanying drawing, forming a part thereof.

The figure is a perspective view of a swivel clamp showing my new design.

I claim:

The ornamental design for a swivel clamp for razor strops or the like substantially as shown.

GEORGE U. WIEFFENBACH.
